UNITED STATES PATENT OFFICE.

HOWARD J. OTIS, OF WALTON, OREGON.

ANTISLIPPING DEVICE.

1,084,957.

Specification of Letters Patent.

Patented Jan. 20, 1914.

Application filed August 20, 1913. Serial No. 785,809.

To all whom it may concern:

Be it known that I, HOWARD JENKINS OTIS, a citizen of the United States, residing at Walton, in the county of Lane and 5 State of Oregon, have invented certain new and useful Improvements in Antislipping Devices; and I do hereby declare the following to be a full, clear, and exact description of the invention, such as will enable 10 others skilled in the art to which it appertains to make and use the same.

My invention relates to antislipping devices to be worn upon the sole of a shoe, and has for its object the provision of a plurality of vacuum cups forming the bearing 15 surface of the device, whereby the gripping action is provided to prevent slipping.

A further object of my invention is to provide a device of the above mentioned 20 character, which is reinforced at the point where it engages the edges of the sole of the shoe, in such a manner as to prolong the life of the device.

A still further object of my invention is 25 to provide a device of the above mentioned character, which is simple as to construction and cheap to manufacture and therefore more commercially desirable than antislipping devices as at present in use.

With these and other objects in view as 30 will become more apparent as the description proceeds, the invention consists in certain novel features of construction, combination and arrangement of parts as will be 35 hereinafter fully described and claimed.

For a complete understanding of my invention, reference is to be had to the following description and accompanying drawings, in which—

40 Figure 1 is a bottom plan view illustrating my device attached to a shoe, Fig. 2 is a side elevation, Fig. 3 is a vertical sectional view taken on line 3—3 of Fig. 1, and Fig. 4 is a plan view of a slightly modified form 45 of my invention.

Referring to the drawings, the numeral 1 designates the body portion of my device, which is constructed of rubber of suitable thickness and is preferably rectangular in 50 shape, and so formed as to conform to the shape of the bottom of the shoe sole.

A plurality of annular cups 2 are formed upon the outer surface of the body portion 1, in such a manner as to provide vacuum 55 chambers when subjected to pressure. The suction cups 2 are vulcanized or formed in

any suitable manner upon the body portion 1 and are arranged close to each other to provide an efficient friction and gripping surface. 60

Formed integrally with the body portion 1 is a reduced elastic strap member 3, which is adapted to be fitted about the upper toe portion of the shoe, designated A as an entirety, and which serves to securely hold the 65 device in operative position upon the shoe. The elastic strap member 3 is reduced intermediate its ends, thus the portion that fits about the upper face of the shoe in being reduced is not apt to be wrinkled and is 70 less conspicuous at that point.

It is apparent that the strap portion 3 in being of an elastic nature to facilitate its engagement with the shoe is relatively thin with relation to the body portion, and that 75 a great strain thereon would be had at the point where it engages the side edges of the shoe sole, and in this connection this invention employs a thickened reinforcing portion 4 upon each side of the strap 3 adjacent the point of its formation with the body portion and of its engagement with the side edges of the shoe sole. 80

The reinforcing portions 4 are reduced at their upper terminals as at 5, and the upper 85 terminals thereof extend to a point near the upper surface of the strap 3. It will thus be seen that the life of the elastic strap 3 is prolonged by the construction and arrangement of the reinforcing portions 4, 90 and that the device is readily applicable to the shoe through the medium of the elasticity of the strap 3.

A modified form of my invention as illustrated in Fig. 4, consists of the provision 95 of diamond shaped vacuum cups 6, instead of the annular cups 2 employed in connection with my preferred form.

It may be desirous to use diamond cups in preference to the annular cups for the purpose of decoration or design and for this reason the provision is made for the use of diamond shaped cups. 100

In reduction to practice, I have found that the form of my invention, illustrated 105 in the drawings and referred to in the above description, as the preferred embodiment is the most efficient and practical; yet realizing that the conditions concurrent with the adoption of my device will necessarily vary, 110 I desire to emphasize the fact that various minor changes in details of construction,

proportion and arrangement of parts may be resorted to, when required, without sacrificing any of the advantages of my invention, as defined in the appended claim.

3 Having thus described my invention, I claim:

An anti-slipping device for shoes comprising an approximately rectangular body portion, a plurality of suction cups formed integral with the body portion, an elastic strap formed integral with the sides of the body portion and reduced in width intermediate its terminals and arranged to se-

cure said body portion to the shoe, and means for reinforcing said strap at the point 15 of its formation with the body portion, comprising a thickened portion formed integrally with the strap and body portion and reduced in width at its upper terminal.

In testimony whereof I affix my signature 20 in presence of two witnesses.

HOWARD J. OTIS.
